ENOCH OHNSTRAND, OF KENMORE, AND BENJAMIN G. RAND, OF NORTH TONAWANDA,
NEW YORK, ASSIGNORS TO REMINGTON RAND INC., OF NEW YORK, N. Y.

FURNITURE CONSTRUCTION

Application filed November 28, 1927. Serial No. 236,129.

This invention relates to improvements in the construction of furniture, particularly metal furniture such as desks and the like.

An object of the invention is to provide a furniture construction having a top section and a body section detachably associated and secured in assembled relation by suitable movable latching means.

A further object of the invention resides in forming the body portion of a piece of furniture with openings adjacent the upper edge in which suitable movable latch members are removably engaged for detachably locking a top section on the body portion.

Another object of the invention resides in providing movable latch members for locking the top section to the body portion of a piece of furniture, such as a desk or the like, in which the latch members are provided with suitable locking means for locking the latch members in engaged relation, and in which the latch members and the locking means are normally concealed and accessible for operation through the use of a special tool.

The invention comprehends numerous other objects residing in the details of construction and relation of the parts which are more particularly pointed out in the following detailed description, and in the claims directed to a preferred form of the invention, it being understood however, that the latches may be arranged in any desired manner and that various changes in the construction and association of the parts may be made without departing from the spirit and scope of the invention as herein set forth.

In the drawings forming part of this application:—

Fig. 1 is a perspective showing part of an assembled desk equipped with this invention.

Fig. 2 is a horizontal sectional view looking upwardly, taken from below the desk top through one corner portion of the desk, the latches being shown in engaged position.

Fig. 3 is a detailed sectional view taken substantially on the line 3—3 of Fig. 2, por-

tions being broken away for convenience in illustration.

Fig. 4 is an end elevation of the operating tool for the latch members.

Fig. 5 is a side elevation of the tool shown in Fig. 4.

A metal desk construction is illustrated in Fig. 1 which includes a top section 1 and a body portion 2 which are formed for detachable engagement with one another. The body portion 2 includes corner sections 3 between which drawers 4 and the side wall sections extend in the usual manner as is well-known in the construction of metal desks. At the upper end portions, these corner sections 3 are formed with slots 5 as clearly illustrated in Fig. 3.

The top section 1 is formed of a main top plate 6 having depending flange portions 7 extending around the edge thereof, terminating in inwardly extending flanges 8. These flanges 7 and 8 are strengthened by the use of the channel members 9 for providing a rigid edge construction for the top section. Suitable layers 10 may be mounted on the plate member 6 to finish the top section and provide a writing surface thereon in a manner well-known in the art.

When the top section is applied to the body portion, the flanges 7 and 8 and the channel member 9 extend downwardly around the upper edge portion of the body portion 2 of the desk. These flanges are proportioned so that the lower flange on the channel member 9 inside of the flange 8 extends below the slots 5 in the body portion, in assembled relation of the top section on the body portion as shown in Fig. 3.

Retaining levers 11 are pivoted inside of the channel member 9 at one end as indicated at 12, while the opposite ends are provided with laterally extending tapered tongues 13 adapted to extend through and engage in slots 5. As shown in Figs. 2 and 3, these levers are normally concealed within the top section of the desk and to provide access for engaging and disengaging these levers in the slots 5, the flange 8 and adjacent portion of channel member 9 are formed with a slot extending transversely of flange 8 adjacent the

free end of each lever as indicated at 14 with which registers the opening 15 formed in the free end of the lever.

Between the pivot 12 for the levers 11, and the slot 14, the flange 8 and adjacent channel member 9 are formed with an opening 16, in which engages a locking plunger 17 carried by the lever. This plunger 17 has a reduced extension 18 slidably engaged in the cylindrical casing 19, having one end mounted in the lever. The opposite end of the casing is closed and slidably receives the extension 18 of the locking plunger, which is formed with an enlarged head 20 for engaging the end of casing 19 and limiting its projection into opening 16. A coil spring 21 is mounted over the reduced extension 18 and has one end engaged against the plunger 17 and the opposite end seated in the casing 19 so that the spring which is normally under compression, will normally tend to force the plunger downward for engaging in the opening 16. This opening is positioned to receive the plunger 17 when the locking tongue 13 is in the engaged position in slot 5 for locking the top section to the body portion. The head of plunger 17 engaging in opening 16 is rounded to permit ready engagement and disengagement of the plunger from the opening 16 during operation in a manner as will be hereinafter set forth.

Any number of these locking levers may be used on the top section 1 which may be found desirable, and they may be located at the corner portions and throughout the central portions of the top section as found most desirable. The tongues 13 are tapered as shown in Fig. 3 in order that the top section will be drawn tightly into contact with the body portion when they are in assembled relation with the locking levers in the engaged position as shown in Fig. 2.

The tool illustrated in Figs. 4 and 5 is used to engage and disengage these levers from the locking position shown in Figs. 2 and 3. For this purpose, the tool comprises a bar member 22 having a handle portion 23 at one end and having a pair of lugs 24 and 25 respectively, at the opposite end. The lugs 24 and 25 are spaced apart a distance equal to the distance between the centers of the opening 16 and the slot 14. The lugs 24 and 25 project an unequal amount from opposite sides of the bar member 23 as shown in Fig. 4, the lugs 24 being longer than the lugs 25 as illustrated. With this tool, the lugs on one side of the bar are used for operating one of the locking levers, the lug 25 being inserted in opening 16 so that it will substantially disengage the locking plunger 17 from the opening 16 to the extent that a movement of the lever will cause the rounded end to ride upwardly through engagement with the edge of the opening to a fully released position. With lug 25 engaged in opening 16 for par-

tially disengaging locking plunger 17, the lug 24 may be engaged in opening 15 in the locking lever, so that the subsequent pivotal movement of the bar 22 on the lug 25 as a pivot will move the locking lever from the locked to the unlocked position, or vice versa. In using levers as shown in Fig. 2 at the corner of the desk, it is necessary to extend these levers in relative opposite directions which necessitates a reversal of the position of the slot 14 relative to opening 16 so that the lugs 24 and 25 on one side of bar 22 are used in operating one locking lever extending in one direction while the lugs on the opposite side of the bar are used in operating the other locking lever extending in the opposite direction.

The levers 11 are formed adjacent the tongues 13 with angular shoulders 26. These shoulders 26 are adapted to engage the face of the corner posts 3 of the desk in the assembled relation of the parts as shown in Fig. 2 in order to properly position the desk top relative to the corner posts and prevent lateral movement thereof, which would otherwise be permitted by the space between the flanges 8 and the corner posts. When the latches 17 are in locked position as shown in Fig. 2, these levers are rigidly held by these latches so that a firm locking action is obtained through the medium of the levers for locking the top to the body portion of the desk.

From the structure as shown in the drawings, it will be seen that the locking levers are concealed within the top section and require the use of the special tool for attaching and detaching the top section from the body portion. It will be further noted that the depending flange extending around the edge of the top section terminates below the slots 5 so that all of the locking mechanism is concealed from view with the exception of the slots 14 and opening 16 for receiving the lugs of the tool which operate the locking levers. The plungers 17 further operate through their engagement in openings in the locking levers and the openings 16, in which the plungers are seated and extend transversely to the direction of movement of the locking levers, for effectively locking said levers in the engaged relation in slots 5, and effectively retaining the top section locked on the body portion.

What is claimed is:—

1. Furniture, comprising a body portion having corner sections, each corner section having openings formed adjacent the upper end, a top section mounted on said body having a depending flange encircling the upper end of the body, a lever pivoted on said flange and adapted to engage in one of said openings for locking the top on the body, and means for retaining the lever in top locking position.

2. In a furniture construction, a body portion having corner sections, each corner section having openings adjacent the upper end, a top section having depending portions engaged over the openings in each corner section, a movable member mounted on each depending portion having a tongue for engagement in one of said openings to lock the top section on the body portion, and means for retaining the member in locked position. 70
3. In a furniture construction, a body portion having openings at spaced intervals adjacent the upper edge, a top section mounted on said body and having an over-hanging margin, means movably mounted on said margin for engaging in said openings to lock the top section on said body, and means for retaining the last-named means in locked position. 75
4. In a furniture construction, a body portion having openings at spaced intervals adjacent the upper edge, a top section mounted on said body, a series of levers pivotally mounted on said top section in concealed relation, each lever having a portion adapted for engagement in one of said openings for locking the top section on the body portion, and means for retaining said levers in locked position, said means being manually disengagable. 80
5. In a furniture construction, a body portion having openings at spaced intervals adjacent the upper edge, a top section mounted on said body, movable locking members concealed in said top section and adapted to engage in said openings for locking the top on the body, means for retaining said members in top locking position, and an operating member formed for detachable engagement with said members and means for disengaging said means from locking position and moving said members out of engagement with said openings. 85
6. In a furniture construction, a body portion having openings at spaced intervals adjacent the upper edge, a top section mounted on said body portion, levers pivoted on said top section for engagement in said openings to lock said top section on the body portion, and resiliently projected retaining elements carried by said levers for engagement in sockets formed in said top section to retain said levers in locking position. 90
7. In a furniture construction, a body portion having openings adjacent the upper edge, a top section mounted on said body portion having the edge portions extending beyond the body, levers pivotally mounted on said edge portion for locking engagement in said openings, and resiliently projected locking elements movable transversely to the movement of the levers for engagement in openings formed in the top section to lock said levers in top locking engagement in said openings. 95
8. In a furniture construction, a body portion having openings adjacent the upper edge, a top section mounted on said body portion having the edge portion projecting beyond the body portion, said top section having a depending marginal flange terminating in an inwardly extending flange in spaced parallel relation below the top section, levers pivotally mounted on the upper face of said inwardly extending flange for locking engagement in said openings for locking the top section on the body portion, and resiliently projected latches mounted on said levers and adapted to engage in openings formed in said inwardly extending flanges to retain said levers in locking position. 100
9. In a furniture construction, a body portion having openings adjacent the upper edge, a top section mounted on said body portion having the edge portion projecting beyond the body portion, said top section having a depending marginal flange terminating in an inwardly extending flange in spaced parallel relation below the top section, levers pivotally mounted on the upper face of said inwardly extending flange for locking engagement in said openings for locking the top section on the body portion, and resiliently projected latches mounted on said levers and adapted to engage in openings formed in said inwardly extending flanges to retain said levers in locking position. 105
